UNITED STATES PATENT OFFICE.

THOMAS CONNELL, OF IOWA CITY, IOWA.

DAMPER-REGULATOR.

1,274,511.

Specification of Letters Patent.

Patented Aug. 6, 1918.

Application filed May 7, 1917. Serial No. 167,113.

To all whom it may concern:

Be it known that I, THOMAS CONNELL, a citizen of the United States, and resident of Iowa City, in the county of Johnson and 5 State of Iowa, have invented a certain new and useful Damper-Regulator, of which the following is a specification.

The object of my invention is to provide a draft door or damper regulator of extremely simple and durable and inexpensive 10 construction adapted for use with heating systems of the vapor type.

A further object is to provide such a device adapted to automatically raise or lower 15 a draft door or operate a damper according to the pressure in the boiler.

Still a further object is to provide such a device of the type having a receptacle communicating with the boiler, which receptacle 20 has a by-pass overflow outlet, and is also provided with an interior partition so arranged as to divide the receptacle into comparatively large and small parts, and to provide a movable receptacle communicating 25 with the upper portion of the small compartment, whereupon the large compartment is the only one communicating with the boiler.

A further object is to provide a gage for 30 showing the position of the fluid in the large compartment.

It is another object to connect the movable receptacle with a draft door and damper or both.

With these and other objects in view my 35 invention consists in the construction, arrangement and combination of the various parts of the device, whereby the objects contemplated are attained, as hereinafter more 40 fully set forth, pointed out in my claims, and illustrated in the accompanying drawings, in which:

Figure 1 shows a front elevation of a 45 boiler and furnace equipped with a damper and draft regulator, embodying my invention.

Fig. 2 shows a front elevation of the damper regulator device.

Fig. 3 shows a vertical, sectional view 50 taken on the line 3—3 of Fig. 2, and

Fig. 4 shows an enlarged, sectional view of the joint through which water flows from the small compartment to the movable receptacle.

In the illustration of my invention shown 55 in the accompanying drawings, I have used the reference numeral 10 to indicate generally the furnace for heating the boiler 10^a.

The furnace has a draft door 11 and in the smoke pipe a damper 12, both being arranged to be normally closed by gravity and to be opened by pulling on the chains 13 and 14.

Suitably arranged is a support 15, at the upper end of which is mounted a receptacle 15 having a partition 17 extending across its interior, provided with a passage 18 in its lower end which affords communication between the large compartment 19 and the small compartment 20 into which the receptacle 16 is divided by the partition 17. The boiler 10 is connected with the upper interior of the large compartment 19 by means of a pipe 21. A by-pass overflow pipe 22 extends through the side wall of the upper compartment 19 at the upper end thereof and communicates with the pipe 21 at a point below the outlet from the compartment 19.

It will be noted that the pipe 21 extends 80 through the top of the receptacle 16, as clearly shown in Fig. 3.

Communicating with the upper and lower portions of the interior of the large compartment 19 is a suitable gage 23 for indicating the height of water in the compartment 19.

The upper wall of the compartment 20 is provided with an opening to receive a screw-threaded plug 24 having an opening through 90 it contracted at its inner end at 25.

Rotatably mounted in the plug 24 is a tube 26 having an annular flange 27 at its inner end.

Screwed into the outer part of the plug 95 24 is a collar 28 between which and the inner portion of the plug 24 is a suitable packing 29.

Mounted on the outer end of the tube 26 and communicating therewith is a pipe 30. 100 The pipe 30 extends in both directions from the tube 26, and has on one end an adjustable weight 31, capable of being locked in various positions on the pipe 30 by means of a set-screw 32. On the opposite end of the 105 pipe 30 is a container or receptacle 33, the lower end of which communicates with the pipe 30. The receptacle 33 is provided in

its upper surface with a small escape opening 34. The receptacle 33 is connected by the chain 13 with a draft door 11, and by a chain 14 with the arm 35 which operates the damper 12. The chain 14 extends over suitable guide pulleys 36, as shown in Fig. 1.

The relative weights and positions of the weight 31 and the receptacle 33 are such that when the receptacle 33 is empty, the weight 10 31 will be in its downward position and will hold the receptacle 33 in raised position for permitting the damper 12 to be closed by gravity and for opening the draft door 11.

When in this position the receptacle 33 is 15 above the water level in the receptacle 16.

Mounted in the wall of the receptacle 16 is a bolt or the like 37 on which is centrally mounted a plate 38 having in its ends opposite slots 39 curved on the arcs of a circle 20 having its center at the center of the bolt 37.

Spaced horizontally from the bolt 37 on opposite sides thereof are bolts 40 mounted in the wall of the receptacle 16 and extended through the slots 39. It will be seen that 25 the plate 38 may be tilted on the bolt 37 and that its movement is limited by the bolts 40 extended through the slots 39.

Extending outwardly from the outer ends of the plate 38 near the upper edge thereof 30 are lugs 41. Extending through the left-hand lug 41, as shown in Fig. 2, is a screw-threaded bolt 42, adapted to engage the tube 30 between the pivotal point thereof and the weight 31.

Extending through the other lug 41 is a 35 similar bolt 42. Both of said bolts are designed to be adjusted. On the last described bolt 42 is a coil spring 43 adapted to engage the tube 30 between the pivotal point there- 40 of and the container 33.

On the bolts 40 are nuts 44. By loosening the nuts 44, the position of the plate 38 may be adjusted considerably. It will thus be seen that the plate 38 and the parts con- 45 nected therewith form a limiting mechanism for limiting the rocking or tilting movement of the tube 30.

The spring 43 forms a cushioning device for the tube 30 at the downward limit of 50 the movement of the end of said tube which supports the container 33.

I have built the receptacle 16 in the manner shown with the partition 17 for forming the compartments 19 and 20, for making 55 a more efficient device.

I have found from experiments that it is advisable to have the receptacle 16 large enough to hold a considerable amount of the water of condensation.

60 It will be obvious that the water will collect in the receptacle 16 until it reaches the height of the pipe 22; thereafter considerable pressure from the boiler will force the water in the compartment 19 downwardly, thereby forcing the water out of the com-

partment 20. It will be seen that the comparatively slight layer of water in the compartment 19 will force out the water contained in the compartment 20 into the tube 30 and the container 33.

The parts are of such relative size that even where the container 33 is entirely filled there will still be water in the compartment 19, and at all times the gage 23 will show accurately the height of the water in the 75 compartment 19.

The arrangement with the partition 17 makes the operation of the damper and draft regulator more uniform and steady than is otherwise the case.

It will readily be seen that when the pressure in the boiler becomes high and the water is forced into the container 33, the container 33 will move downwardly thereby permitting the draft door 11 to close and open the 80 damper 12, for shutting off the draft through the furnace, thereby reducing the heat applied to the boiler.

It will be noted, however, that the container 33 never moves to position where the 90 opening from the tube 30 is lower than the opening from the compartment 20.

The plate 38 may be adjusted, however, for regulating the amount of pressure that is required to cause the container 33 to move. 95

When the boiler pressure goes down, the water will flow back from the container 33 to the compartment 20 and thence to the compartment 19, and in some instances some of the water will pass back through the 100 tube 22 to the boiler. Thus the damper and draft will be automatically regulated for maintaining a constant pressure in the boiler.

The amount of pressure necessary to operate the container 33 may also be varied by adjusting the weight 31.

I claim as my invention:

1. A regulator device comprising a receptacle, a partition on the interior of said receptacle dividing the receptacle into relatively large and small compartments, said partition having a passage in its lower end, a tube communicating with the top of said larger compartment and extending upwardly, thence laterally, thence downwardly and designed to communicate with a boiler and a bypass leading from the upper portion to said upper compartment to the downwardly extending portion of said tube, a 110 third tube rotatably mounted on the wall of said receptacle and communicating with the upper end of the small compartment, a container on one end of said third tube in communication therewith at its lower portion, said container being of less capacity than said receptacle.

2. In a regulator device, comprising a receptacle, a partition therein for dividing said receptacle into relatively large and 115

small compartments, said partition having a passage in its lower portion, a tube communicating with the upper end of the larger compartment and designed to communicate 5 with a boiler, a tube pivotally mounted on said receptacle and arranged in communication with the upper part of said second com-

partment, a second receptacle on said tube arranged with its lower portion in communication therewith, said second receptacle being of smaller capacity than said first receptacle. 10

Des Moines, Iowa, April 26, 1917.

THOMAS CONNELL.
